UNITED STATES PATENT OFFICE.

EDWARD B. ELLICOTT, OF CHICAGO, ILLINOIS.

SIGNAL-TRANSMITTING SYSTEM.

SPECIFICATION forming part of Letters Patent No. 738,302, dated September 8, 1903.

Application filed January 13, 1902. Serial No. 89,501. (No model.)

To all whom it may concern:

Be it known that I, EDWARD B. ELLICOTT, a citizen of the United States, residing at Chicago, in the county of Cook and State of Illinois, have invented a certain new and useful Improvement in Signal - Transmitting Systems, (Case No. 3,) of which the following is a full, clear, concise, and exact description, reference being had to the accompanying drawings, forming a part of this specification.

My invention relates to signal-transmitting systems, and has for its object the provision of an improved means whereby a plurality of stations in electrical communication with a central office may be selectively actuated to convey the desired information.

My invention is more particularly applicable to systems wherein a plurality of circuits emanate from a central station and it is desired by means of a single signal-sending apparatus to impress signals upon any of the circuits entering said central office without disturbing those circuits to which it is undesirable to convey the said signal or information.

My invention may, for instance, in one embodiment thereof be employed in connection with the various quarters for the engine or truck companies of a fire department in which it is desirable to arrange a certain number of individual circuits, each of which enters or is led to a central office, each of said circuits containing in series the signaling apparatus of a given number of stations throughout the department. The signal-receiving apparatus on one circuit comprising, say, for instance, fifteen engine or truck companies are thus conjointly actuated when a signal - sending instrument of said circuit is actuated, each of said circuits also having a signal-receiving instrument at the central office. Each company upon leaving quarters or returning to quarters or upon the performance of any special duty is required to transmit this intelligence to the central office, at the same time transmitting this intelligence to all the other engine or truck companies on the same circuit. This intelligence which is thus received at the central office must then be transmitted to all of the remaining companies of the fire department, so that each company is at all times ap-

prised of the fact whether a companion company is at home or on duty at a fire or performing some special duty. It is undesirable in re-transmitting intelligence received to the companies not on the original circuit to retransmit this intelligence to those companies which have already received this intelligence by being on the circuit of the company originally transmitting the same. To accomplish this and yet retain the advantage of having a single signal-sending instrument actuate all the signal-receiving instruments throughout the entire fire department except those upon a particular circuit which has been cut out, which signal-sending instrument is adapted to practically simultaneously actuate all of the said signal-receiving instruments, I employ in association with each separate and independent circuit an actuating-key, which actuating-key is controlled by an electromagnet, all of which controlling-electromagnets are included in parallel with a source of current and a master-key. The preferred means which I employ to cut out any of the circuits or circuit so that the actuation of the master-key will not actuate the signal-receiving instruments on said circuit consists in the provision of switching mechanism serially including contacts in each one of the parallel circuits of the controlling - electromagnets, which switching mechanism by its position removes the controlling-electromagnet which it is desired to cut out from the main controlling-circuit.

Further objects of my invention are the provision of simple and improved means whereby no more manual effort is required to actuate all of the receiving instruments throughout the department than is required to actuate the instruments along a single circuit.

Further objects and advantages of my invention will be hereinafter set forth. I will explain one embodiment of my invention as applied particularly to fire-alarm circuits in connection with the accompanying drawings, in which—

Figure 1 is a diagrammatical view showing the arrangement of the complete system. Fig. 2 is a detailed view of the switch-actuating key with its associated springs.

My invention, as shown in the drawings, is

- adapted more particularly for use in signaling between the various stations of the fire department. A central signal receiving and sending station *a* is shown, at which station 5 there is provided a battery 1 and an actuating-key 2, which is adapted to control the flow of current from said battery through a plurality of circuits *b b' b²*, &c., which are connected in parallel relation. Each of the circuits *b* 10 *b' b²*, &c., has a switch, respectively, *c c' c²*, &c., included serially in circuit therewith. The switches are preferably mounted in circular form beneath a dial, concentrically with which switches I prefer to mount an actuating-handle 3, which, depending upon the position of said handle upon the said dial, serves to open one or the other of the said switches *c c' c²*, &c., thus opening one of the associated circuits thereof *b b'*, &c. 15
- 20 The actuating-handle 3 is provided, preferably, with an insulating-button 4, which by engagement with the spring portion 4' of either of the switches *c c'*, &c., removes or opens the contacts of the said switches. The 25 controlling-switch, comprising the actuating-handle 3 and the switches *c c'*, &c., thus by its position serves to open the circuit through either one of the subcircuits *b b'*, &c., so that when the master-key 2 at the station *a* is depressed 30 current is passed over all of the said subcircuits excepting the particular one which is opened by the handle 3. The master-key thus constitutes a unitary means for effecting the propagation of signaling-current over a plurality of signaling-circuits. 35
- Each of the subcircuits *b b'*, &c., includes serially the helix of an electromagnet *d d'*, &c., which is energized when current passes through the said subcircuits upon depressing the key 2 at the main station *a*. The electromagnets *d d'*, &c., are preferably placed below a plurality of key-contacts *e e'*, &c., which may preferably be in the style of the well-known Morse key, similarly to the key 2 at 40 the main station *a*. The said Morse keys *e e'*, &c., are serially included with a suitable source of current *f* and with a plurality of substations of the department. 45
- I have shown more in detail the arrangement of a plurality of stations as associated with the keys *e* and *e'*, the stations associated with the remaining keys being omitted for the sake of clearness. The keys have contacts 5 5, which close circuit through the battery *f* to include in the subcircuit controlled by the said key the signaling and receiving apparatus at the substations *e₁ e₂ e₃*, &c., the signal sending and receiving apparatus at each substation preferably consisting of the 55 ordinary telegraph key and relay. 60
- A signal-receiving instrument in the shape of a relay 6 or 6' is preferably located at the central station and included in each of the substation-circuits to receive signals sent by 65 the substations and also to indicate and warn when a substation-circuit is open due to a

broken wire or the like. The armature and contact of said relay may be included in circuit with a lamp, bell, or other indicating device. 70

It will be seen that with the construction as herein illustrated if the switch-arm 3 with its associated button 4 depresses part 4' of switch *c'*, for instance, a depression of the master-key 2 at the station *a* will energize all 75 of the electromagnets *d d'*, &c., excepting, of course, the electromagnet *d'*, which is cut out of circuit, due to the position of the switch *c'*. Each of the remaining electromagnets *d d'*, &c., being energized, their associated contact-keys *e e'*, &c., are attracted, whereby circuit is made or broken through the respective subcircuits included with the said keys, thereby actuating each one of the signal-receiving instruments at all of the substations 80 of the department, excepting those which are included in the circuit associated with the key *e'*. 85

To illustrate the usefulness of my invention in connection with systems of this sort, 90 I will give a specific example of the manner in which the same may be employed. It is essential that each station of a fire department be apprised of all the movements of the apparatus at the associated stations of the 95 department, so that the conduct of said station may be regulated accordingly. It is also necessary that each substation inform the main office when the apparatus at said station returns from a fire or performs special 100 duties of other kinds. It will be apparent that if station *e₁*, for instance, sends a message to the central office said message will while being received at the central office be also received at each of the stations *e₂ e₃*, &c., 105 which are upon the same circuit. This signal, however, which is received at the central station *a* must be transmitted to all those stations of the department which have not already received the signal—that is, those stations associated, respectively, with the controlling-magnets *d' d²*, &c. The switch-arm 3, with its contact 4, is thus moved to depress the part 4' of switch *c*, thus cutting out the circuit which has transmitted the signal, 110 whereafter the master-key 2 is manually actuated to send the signal or message thus received to the remaining stations of the department through the agency of the electromagnets *d' d²*, &c., with their associated 115 circuits. 120

The advantages of my improved system whereby it is possible to transmit intelligence to a plurality of circuits without the necessity of manually-operated keys in each circuit will thus be apparent. It is obvious that by placing the handle 3 in proper position the master-key may be actuated to convey intelligence over all of the circuits, if desired, instead of cutting out one or the other of the 130 actuating means controlling the subcircuits. The construction of the actuating means of

my invention is also such that the central office, at which the keys *e e'*, &c., are located, may transmit intelligence along either one of the circuits controlled by the said keys simply by manually actuating said keys, as described.

While I have thus shown and described one embodiment of my invention as applied to a specific case, I do not wish to limit myself to such application nor to the precise embodiment thereof herein shown; but,

Having thus described my invention, I claim as new, and desire to secure by Letters Patent, the following:

1. In a signaling system, the combination with a plurality of subcircuits, each of said subcircuits including a plurality of signal-receiving instruments, of a key associated with each of said subcircuits to impress signaling-currents thereon, a source of current associated with said subcircuits, electromagnets associated with said keys to cause the operation thereof upon being energized, a main circuit in which said electromagnets are included, a source of current in said main circuit, a master-key in said main circuit for controlling a simultaneous operation of said electromagnets, whereby signaling-current is impressed upon all the said subcircuits, and switching mechanism for rendering any one of said electromagnets irresponsible to actuations of said master-key, substantially as described.

2. In a signaling system, the combination with a plurality of subcircuits including a plurality of signal receiving and sending instruments, of a key associated with each of said subcircuits to impress signaling-currents thereon, a source of current associated with said subcircuits, a relay included in each of said subcircuits for indicating the operative condition of said circuits, electromagnets associated with said keys to cause the operation thereof upon being energized, a main circuit in which said electromagnets are included, a source of current in said main circuit, a master-key in said main circuit for controlling the simultaneous operation of said electromagnets, whereby signaling-current may be impressed upon all of the subcircuits, and switching mechanism for rendering any one of the said electromagnets irresponsible to actuations of said master-key, substantially as described.

3. In a signaling system, the combination with a plurality of subcircuits, each of said subcircuits including a plurality of signal-receiving instruments, of a key associated with each of said subcircuits to impress signaling-currents thereon, a source of current associated with said subcircuits, electromagnets associated with said keys to cause the operation thereof upon being energized, a main circuit in which said electromagnets are included, a source of current in said main circuit, a master-key in said main circuit for controlling a simultaneous operation of said

electromagnets, whereby signaling-current is impressed upon all the subcircuits, a switch for rendering any one of said electromagnets irresponsible to actuations of said master-key, substantially as described.

4. In a signaling system, the combination with a plurality of subcircuits including a plurality of signal receiving and sending instruments, of a key associated with each of said subcircuits to impress signaling-currents thereon, a source of current associated with said subcircuits, a relay included in each of said subcircuits for indicating the operative condition of said circuits, electromagnets associated with said keys to cause the operation thereof upon being energized, a main circuit in which said electromagnets are included, a source of current in said main circuit, a master-key in said main circuit for controlling the simultaneous operation of said electromagnets, whereby signaling-current may be impressed upon all of the subcircuits, a switch for rendering any one of said electromagnets irresponsible to actuations of said master-key, and a plurality of contacts for said switch, one of said contacts being included serially in circuit with each of said electromagnets, substantially as described.

5. In a signaling system, the combination with a plurality of subcircuits, each of said subcircuits including a plurality of signal-receiving instruments, of a key associated with each of said subcircuits to impress signaling-currents thereon, a source of current associated with said subcircuits, electromagnets associated with said keys to cause the operation thereof upon being energized, a main circuit in which said electromagnets are included, a source of current in said main circuit, a master-key in said main circuit for controlling a simultaneous operation of said electromagnets, whereby signaling-current is impressed upon all the subcircuits, a switch for rendering any one of said electromagnets irresponsible to actuations of said master-key, and a plurality of contacts for said switch, one of said contacts being included serially in circuit with each of said electromagnets, substantially as described.

6. In a signaling system, the combination with a plurality of subcircuits, said subcircuits including a plurality of signal sending and receiving instruments and a source of current, of a key associated with each subcircuit for impressing signaling-currents thereon, electromagnets associated with each of the aforesaid keys, adapted to actuate the same upon energization, a source of current and a master-key for controlling the flow of current from said source, circuits for said electromagnets, included in series parallel relation with said source of current and said master-key, and a switch included in the circuit of each electromagnet, whereby to render said electromagnet inoperative, substantially as described.

7. The combination with a plurality of sub-

- circuits each subcircuit including a plurality of signal sending and receiving instruments and a source of current, of a key associated with each subcircuit for impressing signaling-currents thereon, electromagnets associated with each of the aforesaid keys adapted to actuate the same upon energization, a source of current and a master-key for controlling the flow of current from said source, circuits 5 for said electromagnets, the said circuits being included in series parallel relation with the said source of current and said master-key, and a switch included in the circuit of each electromagnet to render the said electromagnet inoperative, said switch including serial contacts in each one of the said electromagnet-circuits said contacts being controlled by the switch-handle of the switch, substantially as described.
- 10 8. In a signaling system, the combination with a plurality of signaling-circuits, of a plurality of electromagnets for sending signals over these circuits, a main circuit including said electromagnets, unitary means in 15 said main circuit for effecting the operation of all the electromagnets, and means whereby the unitary means may be restricted to the substantially simultaneous operation of a lesser number of the electromagnets than all, substantially as described.
- 20 9. In a signaling system, the combination with a plurality of signaling-circuits, of a plurality of electromagnets for sending signals over these circuits, said electromagnets being included in circuits independent of the 25 signaling-circuits, unitary means for effecting the operation of all the electromagnets, and means whereby the unitary means may be restricted to the substantially simultaneous 30 operation of a lesser number of the electromagnets than all, substantially as described.
- 35 10. In a signaling system, the combination with a plurality of signaling-circuits, of a plurality of electromagnets for sending signals over these circuits, the said electromagnets being in circuits independent of the signaling-circuits, unitary means whereby all of the 40 circuits including the electromagnets may be closed, and means whereby the unitary means may be restricted to the substantially simultaneous 45 operation of a lesser number of the electromagnets than all, substantially as described.
- 50 11. In a signaling system, the combination with a plurality of signaling-circuits, of a plurality of electromagnets for sending signals over these circuits, the said electromagnets being in circuits independent of the signaling-circuits, unitary means whereby all of the 55 circuits including the electromagnets may be closed, and means for opening or rendering ineffective a circuit including one of the said electromagnets, whereby the unitary means 60 may be restricted to the substantially simultaneous 65 operation of a number of electromagnets less than all, substantially as described.
12. In a signaling system, the combination with a plurality of signaling-circuits, of a plurality of electromagnets for sending signals over these circuits, a main circuit including said electromagnets, unitary means in said main circuit for effecting the operation of all the electromagnets, and means whereby the unitary means may be restricted to the substantially simultaneous operation of a lesser number of the electromagnets than all, substantially as described. 70
13. In a signaling system, the combination with a plurality of signaling-circuits, of a plurality of electromagnets for sending signals over these circuits, a main circuit including said electromagnets, unitary means in said main circuit whereby all of the circuits including the electromagnets may be closed, and means whereby the unitary means may be restricted to the substantially simultaneous operation of a lesser number of the electromagnets than all, substantially as described. 75
14. In a signaling system, the combination with a plurality of signaling-circuits, of a plurality of electromagnets for sending signals over these circuits, a main circuit including said electromagnets, unitary means in said main circuit for effecting the operation of all the electromagnets, and means whereby one of the said electromagnets may be prevented from sending a signal while the remaining electromagnets are being substantially simultaneously operated by the unitary means, substantially as described. 80
15. In a signaling system, the combination with a plurality of signaling-circuits, of a plurality of electromagnets for sending signals over these circuits, a main circuit including said electromagnets, unitary means in said main circuit for effecting the operation of all the electromagnets, and switching mechanism whereby one of the said electromagnets may be prevented from sending a signal while the remaining electromagnets are being substantially simultaneously operated by the unitary means, substantially as described. 85
16. The combination with a plurality of signaling-circuits, of a plurality of keys or switches for effecting signals in said circuits, electromagnets for operating said circuits, a main circuit including said electromagnets, a master-key in said main circuit for controlling the simultaneous operation of said keys, and switching mechanism for rendering any one of said keys irresponsible to actuations of said master-key, substantially as described. 90
17. The combination with a plurality of signaling-circuits, of a plurality of keys or switches for effecting signals in the circuits, a master-key or switch for controlling the operation of the aforesaid keys, electromagnets for the aforesaid keys controlled by the master-key, a main circuit including said electromagnets and said master key, and switching mechanism for cutting an electromagnet out of circuit, whereby a lesser number than all of the keys may be substantially simulta- 95

neously operated by the master-key, substantially as described.

18. The combination with a plurality of sub-circuits, including sending and receiving instruments, of a plurality of keys at a main station for effecting signals in said circuits, an indicating device included in each of said circuits for indicating the operative condition of said circuits, electromagnets for operating said circuits, a main circuit including said electromagnets, a master-key in said main circuit for controlling the simultaneous operation of said keys, and switching mechanism for rendering any one of said keys irresponsible to actuations of said master-key, substantially as described.

19. The combination with a plurality of sub-circuits, including sending and receiving instruments, of a plurality of keys at a main station for effecting signals in said circuits, an indicating device included in each of said circuits for indicating the operative condition of said circuits, electromagnets for operating said circuits, a main circuit including said electromagnets, a master-key in said main circuit for controlling the simultaneous operation of said keys, a switch for rendering any

one of said electromagnets irresponsible to actuations of said master-key, and a plurality of contacts for said switch, one of said contacts being included serially in circuit with each of said electromagnets, substantially as described.

20. The combination with a plurality of sub-circuits, including sending and receiving instruments, of a plurality of keys at a main station for effecting signals in said circuits, a relay at the main station included in each of said circuits for indicating the operative condition of said circuits, electromagnets for operating said circuits, a main circuit including said electromagnets, a master-key in said main circuit for controlling the simultaneous operation of said keys, and switching mechanism for rendering any one of said keys irresponsible to actuations of said master-key, substantially as described.

In witness whereof I hereunto subscribe my name this 11th day of January, A. D. 1902.

EDWARD B. ELLICOTT.
